UNITED STATES PATENT OFFICE.

CLEMENT EDGAR ECKRODE, OF MILLTOWN, NEW JERSEY, ASSIGNOR TO JOHNSON AND JOHNSON, OF NEW BRUNSWICK, NEW JERSEY, A CORPORATION OF NEW JERSEY.

SURGICAL DEVICE.

No. 923,118.

Specification of Letters Patent. Patented May 25, 1909.

Application filed January 18, 1909. Serial No. 472,872.

To all whom it may concern:

Be it known that I, CLEMENT EDGAR ECKRODE, a citizen of the United States of America, and residing in the city of Milltown, in the county of Middlesex and State of New Jersey, have invented a certain new and Improved Surgical Device, of which the following is a specification.

My invention relates to surgical devices 10 and more particularly to protective appliances for the hands, the special object of my invention being to provide a rubber cot for the fingers and portion of the hand likely to carry or be exposed to infection 15 during gynecological examinations and the like.

In the accompanying drawing I have shown my improved cot in a perspective view as adjusted to the hand in position for 20 use.

It is now customary for the surgeon or physician when making an examination of the character mentioned to put on a rubber glove of the usual type which completely 25 covers the hand and extends well up the forearm. This is more or less of a troublesome operation since these gloves cannot be quickly adjusted and are easily torn. Moreover a glove is unnecessary since the examination is almost invariably made with the index finger alone or at most with the index and second fingers. Less careful physicians frequently make such examinations with no further protection than finger 30 cots. But inasmuch as the latter reach only to the crotch of the fingers and do not cover the palm or back of the hand, infection is apt to be carried either to or from these exposed portions.

My improved cot aims to avoid these disadvantages and at the same time meet all the requirements of the careful physician for the use to which it is intended to be put. My device comprises a rubber cot having (1) 40 a finger portion A, the fingers of which are joined after the fashion of a glove and preferably cover three fingers as shown, and (2) a body portion B which extends well down over the palm and back of the hand, front and back, and is carried down on the side practically to the base of the thumb. The edges of the rubber are finished in any suitable fashion, preferably preserving the elasticity of the rubber to facilitate the 45 adjustment and removal of the cot.

It will be readily seen that for the purposes for which it is intended my improved cot presents all the advantages of a glove, since the hand is covered to the full extent to which it is exposed, while it may be much more 60 readily adjusted, even more readily than separate finger cots since the body portion serves as a convenient flap by which the cot may be drawn onto the fingers simultaneously. The cot is furthermore reversible and 65 may therefore be used on either hand, thus dispensing with the necessity for a pair of cots, as is necessary when using gloves. In this connection the cot may be either reversed so that the portion which covers the 70 palm of one hand will cover the back of the other hand when adjusted on the latter, or the cot may be turned inside out so that the same portion will cover the palm of each hand. In addition to the fact that a single 75 cot may be used on both hands, the device will further commend itself on the ground of economy, since it can be marketed at a much lower figure than a pair of gloves.

Obviously the usefulness of the cot is not 80 confined to gynecological examinations, for which purpose it is however, especially adapted. It may be employed in the exploration of small wounds, the mouth, throat and in other situations where but one or two fingers 85 are employed and the exposure to infection is not great.

Modifications of the precise structure shown may be made without departing from the scope of my invention as set forth in the 90 following claim.

I claim as my invention:

A rubber cot for the uses specified, comprising a finger portion protecting some but not all of the fingers of the hand and a body portion integral therewith partially covering the palm and back of the hand so as to isolate the same from infection, the free margins of the body portion being suitably finished to prevent injury to the same and to facilitate 100 the adjustment of the cot, substantially as described.

In testimony whereof I have signed my name to this specification, in the presence of two subscribing witnesses.

CLEMENT EDGAR ECKRODE.
